SOLE PRESSING PAD

Frank R. Merritt, Haverhill, Mass., assignor to
United Shoe Machinery Corporation, Paterson,
N. J., a corporation of New Jersey

Application July 29, 1935, Serial No. 33,672

17 Claims. (Cl. 12—38)

This invention relates to improvements in pads for use in applying pressure to shoe bottoms and is illustrated herein as embodied in pads particularly adapted for applying leveling pressure to the outsoles of shoes.

In leveling shoe bottoms it is important that the leveling pressure be applied in such a way as to smooth out and remove irregularities of the outsole without reproducing on the tread surface of the outsole irregularities on the surface against which the outsole is laid. Moreover, in shoes having their outsoles attached by stitches, the leveling pressure should be such that it will flatten down the bunches caused by the sole-attaching 10 stitches without wrapping the sole margins too closely around the shoe upper.

Attempts have been made at various times to apply direct sole-leveling pressure to shoe bottoms utilizing as a pressing member a resilient 20 pad composed of rubber or some composition thereof the shoe-engaging surface of which is capable of yielding under pressure. These attempts have not been successful for the reason that resilient yieldable material such as rubber 25 in its natural condition is not adapted to produce the desired results and tends to accentuate the irregularities rather than reduce them. Moreover, when sufficient pressure is applied to the shoe to effect a proper leveling operation under 30 normal conditions, a rubber pad of the type referred to will tend to wrap the margins of the outsole too closely against the shoe upper and thus produce a round bottom shoe.

Objects of the present invention are to provide 35 improved pad structures capable of use in applying direct leveling pressure to shoe bottoms and which will level outsoles without producing the defects referred to above.

In accordance with one feature of the invention 40 there is provided a solid pad member of relatively resilient material having a hard shoe-engaging surface or wall which is capable of flexing somewhat under pressure but which is substantially non-compressible. The shoe-engaging wall, as 45 herein illustrated, is supported by relatively resilient material integral therewith and capable of yielding substantially under pressure. Accordingly, when a shoe is pressed against the shoe-engaging wall the shoe cannot sink into it to cause 50 the outsole to be pressed forcibly against hollows or irregularities which may be present on the shoe bottom and thereby reproduce such irregularities on the bottom surface of the sole. The yieldable material supporting the shoe-engaging 55 wall, however, may be compressed and will thus

permit the wall to be bent into general conformity with the shoe bottom. As the leveling pressure increases the hard surface of the pad will level or smooth out the high spots on the sole without applying any pressure to the low places, therefore 5 by leveling the sole in the proper manner.

In order to assist the hard shoe-engaging wall to conform to the shape of the bottom of a shoe pressed thereon the portion of the yieldable resilient material supporting the marginal portion 10 of this wall is preferably harder than the portion supporting it inwardly of said marginal portion, this marginal material, however, being softer than the shoe-engaging wall. To facilitate the yielding action of these different supporting materials they are separated for a greater part of their thickness by a groove which, as herein illustrated, extends around the marginal portion of the pad and approximates in shape the periphery of the largest shoe which is to be operated upon. 15 Since the pad is adapted to operate on shoes of different styles and having different toe springs and heel heights, it is also provided with a transverse groove arranged to underlie the ball line 20 of a shoe operatively positioned thereon and acting to facilitate angular adjustment of the forepart of the pad relatively to its rear portion. 25

The invention also includes, in accordance with another of its features, a modified form of sole-leveling pad similar in many respects to that 30 described above but having a shoe-engaging wall composed of a hard relatively non-compressible outer layer and a thicker and somewhat yielding inner layer of resilient material, this wall being supported inwardly of its margin by still 35 softer resilient material integral therewith and by relatively hard resilient material at said margin. Preferably the outer surface of the shoe-engaging wall is covered by a thin layer of flexible material such as leather which provides a good 40 surface for engaging the outsole and tends to prevent marking of the outsole.

The invention also provides, in accordance with still another feature, a sole-leveling pad more 45 particularly adapted for operating on shoes having toe springs the angles of which are relatively great, this pad, as illustrated herein, having a relatively hard shoe-engaging surface and being provided with longitudinal grooves located 50 between soft resilient material supporting its shoe-engaging wall inwardly of its margins and harder resilient material supporting said margins, the grooves terminating at a transverse groove coinciding substantially with the tip line of a shoe 55 operatively positioned on the pad. Forwardly of

- the tip line, the shoe-engaging wall of the pad is supported by two continuous layers of resilient material integral with each other and differing considerably in hardness, thereby permitting the toe portion of the shoe-engaging wall to conform itself readily to the shape of the shoe bottom without sufficient bending to cause cracking. The pad is also provided with a transverse groove arranged to underlie the ball line of a shoe operatively positioned thereon to permit the pad to bend into closer conformity with the longitudinal contour of a shoe the forepart of which is located at a relatively steep angle with respect to its shank and heel portion.
- With the above and other objects and features in view the invention will now be described in connection with the accompanying drawings and pointed out in the claims.

In the drawings,

- Fig. 1 is a front elevation of the upper portion of a sole-laying machine in which the pad of the present invention is utilized;

Fig. 2 is a plan view of the sole-leveling pad;

- Fig. 3 is a side elevation of the pad with a portion broken away;

Fig. 4 is a transverse sectional view on an enlarged scale taken through the shank portion of the pad on the line IV—IV of Fig. 3;

- Fig. 5 is a transverse sectional view through the shank portion of a modified form of pad;

Fig. 6 is an enlarged sectional view through the forepart of a shoe prior to the sole-leveling operation;

- Fig. 7 is a transverse sectional view through the forepart of the pad illustrated in Figs. 2 and 3 showing the shoe under sole-leveling pressure, the section being taken on the line VII—VII of Fig. 3;

- Fig. 8 is a plan view of another modified form of sole-leveling pad;

Fig. 9 is a side elevation partly in section of the pad of Fig. 8;

- Fig. 10 is a transverse sectional view on an enlarged scale through the shank portion of the pad, the section being taken on the line X—X of Fig. 9; and

Fig. 11 is a transverse sectional view of the pad on the line XI—XI of Fig. 9 showing the shoe under sole-leveling pressure.

- The illustrated pad is constructed and arranged to apply direct sole-leveling pressure substantially simultaneously to an entire shoe bottom and is particularly adapted for use in a sole-laying machine of the type disclosed in Letters Patent of the United States No. 1,549,243, granted August 11, 1925 upon an application filed in the name of Erastus E. Winkley.

As illustrated in the patent referred to the sole-laying machine is provided with shoe-engaging abutments 20, 22 for engaging lasted shoes and pressing them against pad members mounted in pad boxes 24 carried by the machine and arranged to be moved alternately toward the abutments to bring the shoes into engagement therewith and to cause the soles of the shoes to be pressed against the shoe bottoms. The pad boxes 24 as herein illustrated are of the type disclosed in Letters Patent of the United States No. 2,047,185, granted July 14, 1936, in the names of Milton H. Ballard et al., each pad box being provided with means for adjusting the forepart section of the pad relatively to its rear portion to adapt it for operating upon shoes having different heights of heels. Since the soles are attached to the shoes before the leveling operation

is performed, the sole and shoe-positioning mechanism disclosed in the Ballard patent is omitted.

Each pad box 24 is provided with a lower or supporting pad member 26 which fills the greater part of the box and is preferably composed of relatively firm but resilient rubber as disclosed, for example, in Letters Patent of the United States, No. 2,017,982, granted October 22, 1935, on my application. Resting on top of the pads 26 are pad members 28 which are especially constructed for applying sole-leveling pressure directly to the bottom of a shoe mounted thereon. One of these sole-leveling pads will now be described in detail.

The shoe-engaging surface 30 of the pad 28, as illustrated in Fig. 3, is shaped initially to conform substantially to the longitudinal and transverse curvatures of the bottom of a woman's shoe which is to have a heel of medium height. The toe portion of this surface is nearly parallel to the lower surface of the pad and the shank portion is formed with a substantial bulge having a central hollow or depression (Fig. 4) for engaging the shank portion of a shoe, this portion preferably being shaped to engage the margins of the outsole before contacting with its intra-marginal portion. The heel portion of the surface 30 is relatively flat and slopes rearwardly toward the lower surface of the pad, as shown in Fig. 3. The surface 30 forms the upper side of a shoe-engaging wall 32 the construction of which is best shown in Fig. 4. As illustrated, the wall 32 comprises a plurality of layers of flexible materials formed integrally with lower portions of the pad and extending across the entire width thereof. The top layer of the shoe-engaging wall 32 comprises a relatively thin layer 34 of resilient material such as rubber having a durometer reading of about 95° to 100° so that it is relatively hard and non-compressible but is capable of flexing somewhat without cracking under pressure, this material being commonly referred to as ebonite. The next layer of the wall 32 comprises a sheet of fabric material 36 such, for example, as open weave duck, this layer being initially cemented to the hard layer 34 and having cement on its lower side whereby a second layer 38 of hard rubber or ebonite of the same durometer reading as the layer 34 is secured thereto. Below the hard layer 38 is another layer 40 of fabric the under side of which is cemented to the body portion of the pad.

The portion of the pad which supports the shoe-engaging wall 32 is comprised of two different grades of resilient material such as rubber which differ considerably in degree of hardness, these materials being vulcanized to each other and to the wall 32 in a mold designed for that purpose. The material which supports the central portion of the shoe-engaging wall is composed of relatively soft rubber 42 having a durometer reading of between 35° and 40° which permits this material to compress readily under pressure and to yield a substantial amount. The material supporting the marginal portion of the shoe-engaging wall comprises a rubber composition 44 somewhat harder than the rubber inwardly of said margin and reinforced by a multiplicity of small pieces or scraps of canvas or similar fabric material. This material may be a well-known rubber product called ground deckle strap friction and having a durometer reading of between 55° and 60° so that it is considerably harder and less yielding than the rubber 42 supporting the

central portion of the wall 32 but is not as hard as the ebonite layers 34, 38 of the shoe-engaging wall. Accordingly, when substantial pressure is applied to a shoe mounted on the pad, the soft rubber 42 inwardly of the margins of the shoe-engaging wall 32 will yield more readily than the material 44 supporting its margins thereby causing the wall to be readily conformed to the shape of the shoe bottom, the wall being flexible enough to permit such action. Since the surface 30 is relatively unyielding and non-compressible, the bottom of the shoe cannot sink into it to cause the material of the wall 32 to embed itself in any irregularities which may be present on the bottom surface of the outsole. Moreover, since the relatively hard material 44 supports the margins of the shoe-engaging wall more firmly than the soft material 42 supports the central portion of the wall and thus prevents these margins from being depressed as much as said central portion, the marginal portions of the outsole will receive as much leveling pressure as the central portion thereof without causing said marginal portions to be wrapped too closely around the shoe upper. The shoe-engaging surface of the wall will thus have a leveling or ironing effect upon the bottom surface of the outsole which tends to level any projections or bunches, such, for example, as those which might be caused by the filling material in a shoe bottom or by the stitches which secure the outsole to the insole and upper. To state the operation in another way, the construction of the sole-engaging wall 32 and the arrangement of the soft rubber and harder rubber supporting the different portions of this wall are such that while the wall can bend or flex a limited amount under pressure without cracking and can thus conform to the shape of the bottom of a shoe pressed thereon, it cannot be compressed and, consequently, when the more yieldable materials supporting the central and marginal portions of the wall yield under the sole-leveling pressure, the wall will first conform generally to the longitudinal and transverse curvatures of the shoe bottom and then, as the pressure increases, will tend to level or smooth out any irregularities on the bottom surface of the outsole.

In order that the leveling action on the sole may take place more readily, the yieldable material 42 is separated from the harder rubber composition 44 by a relatively deep groove 46 which conforms approximately in outline to the periphery of a shoe bottom except that it is preferably larger than a shoe. When the soft rubber 42 at the central portion of the pad is compressed under the pressure of the sole-laying machine there will not be an excessive thickness of rubber connecting the soft material 42 to the harder marginal material 44 so that the compressing action of these materials is facilitated and the conformation of the shoe-engaging wall 32 to the shoe bottom is effected without detracting any from its leveling action. As illustrated in Figs. 2 and 3, the forward end of the groove 46 is intersected by relatively shallow outwardly diverging grooves 48 which have no special significance so far as the operation of the pad is concerned and result merely from the presence of supporting members of the grid used in the mold in which the pad is made. The heel end of the pad also has a shallow transverse groove 50 resulting from a supporting member in the mold.

Since the pad 28 is arranged to operate on shoes which may vary widely in shape in their shank portions it is also provided on its lower side

with a transverse groove 52 of less depth than the groove 46, this groove being arranged to lie substantially under the ball line of a shoe operatively positioned on the pad. The transverse groove 52 facilitates the initial adjustment of the shoe-engaging surface 30 into substantial conformity to the longitudinal contour of a shoe bottom.

Figs. 6 and 7 illustrate respectively how a shoe A having its outsole attached by through-and-through stitches 54, illustrated as lockstitches, will appear before and after the sole-leveling operation is performed, Fig. 6 being drawn on an enlarged scale to accentuate the irregularities which might exist on the bottom surface of an outsole 56 after it is stitched to the shoe. As illustrated in Fig. 6, the central portion of the outsole may have irregularities 58 in its bottom surface caused, for example, by filler material 60 or by the unevenness of the stock from which the outsole was made. The stitches 54, which are covered only by a thin channel flap or leaf 62, would also tend to produce humps or bulges similar to that shown at 64. Fig. 7 illustrates the same shoe under leveling pressure and shows how the bulge 64 and the irregularities 58 of Fig. 6 are pressed out and leveled by the pressure of the shoe-engaging wall 32. Fig. 7 is a section taken through the forepart of the pad and consequently the various layers of the materials which make up the pad 28 are shown considerably thinner than they would appear at the shank portion of the pad. The leveling action of the wall 32, however, and the compression of the supporting materials 42 and 44 at the shank and heel portions of the pad will be substantially the same as shown in Fig. 7.

If it should be desired to cause the margins of the outsole to be pressed closer than usual against the shoe upper, the pad may, if desired, be provided with a thin readily removable layer 66 of relatively soft rubber as disclosed in the patent referred to above, thereby permitting the shoe to sink farther into the pad without the use of excessive pressure.

Fig. 5 illustrates another type of pad 68 for use in applying direct leveling pressure to the bottoms of shoes, this pad being similar in many respects to the pad 28 but differing in the construction of its sole-engaging wall 70. The sole-engaging wall 70 of the pad comprises a relatively thin flexible layer 72 of leather such, for example, as pigskin, for engaging the shoe bottom, this layer being cemented to a slightly thicker layer 74 of hard rubber or ebonite having a durometer reading of about 95° to 100°. The ebonite layer 74 is relatively non-compressible but is capable of flexing somewhat without cracking under pressure such, for example, as the direct pressure applied by the sole-laying machine. Underlying the layer 74 is a somewhat thicker integral layer 76 of softer rubber material having a durometer reading of from about 55° to 60° and consequently being more yieldable than the layer 74. These three layers constitute the shoe-engaging wall 70 and are supported by relatively soft rubber 78 inwardly of the margin of said wall, this soft rubber conforming approximately in outline to the periphery of the largest shoe which is to be operated upon. The marginal portion of the wall 70 is supported by rubber composition 80 such as the ground deckle strap friction referred to above, this material, as stated, being fairly hard but being capable of yielding a limited amount under sufficient pressure. The

two supporting materials are separated by grooves 82 extending longitudinally of the pad and being joined at the toe end by a curved groove, these grooves facilitating the compressing action of the supporting materials. A relatively thin readily removable layer 66 may also be provided for operating upon shoes the outsoles of which are to be wrapped fairly closely around the shoe uppers. In use the pad 68 tends to level and iron out any irregularities on the bottom of the outsole in a manner similar to that in which the pad 28 operates, the outer leather layer 72 preventing scarring or marking of the outsole but not interfering with the leveling action of the hard layer 74.

Figs. 8 to 11, inclusive, illustrate still another type of pad for use in applying direct sole-leveling pressure simultaneously to all parts of a shoe bottom. As illustrated in Fig. 8, the pad 84 is similar to the pad 28 and is provided with a shoe-engaging wall 86 the outer surface of which conforms substantially to the longitudinal contour of a shoe bottom, the wall being composed of a plurality of layers which differ considerably in hardness. An outer layer 88 of the sole-engaging wall comprises a thin layer of fairly hard rubber material having a durometer reading of from 80° to 85°. Underlying the thin rubber layer 88 is a relatively thick layer 90 of softer rubber having a durometer reading of between 55° and 60°. Integral with and supporting the central portion of the layer 90 of the shoe-engaging wall is softer rubber material 92 having a durometer reading of from about 35° to 40°, this material conforming approximately in outline to the periphery of a shoe bottom as far forwardly as the tip line of a shoe operatively positioned on the pad. Forwardly of the tip line the soft material 92 extends across the full width of the pad to form a continuous layer 94 which is considerably thinner than the material 92 rearwardly of the tip line, as shown in Fig. 9. Underlying the layer 94 is another continuous layer 96 of rubber composition or ground deckle strap friction having a durometer reading of about 55° to 60° this layer likewise extending across the full width of the pad forwardly of the tip line. The marginal portions of the shoe-engaging wall 86 rearwardly of said tip line are supported by ground deckle strap friction 98 which is separated from the soft inner material 92 by a relatively deep groove 100. As shown in Fig. 8, the groove 100 resembles in outline the periphery of the rear portion of the largest shoe to be operated upon and terminates substantially at the tip line. Extending transversely of the pad at the tip line is a relatively shallow groove 102 separating the hard layer 96 from the soft material which supports the wall rearwardly of the tip line. Another transverse groove 104 is formed substantially under the ball line of a shoe operatively positioned on the pad and a thin readily detachable layer 106 is provided, as described above, for permitting the shoe to sink farther into the pad without the use of excessive pressure when operating on round bottom shoes, the layer 106, as shown in Fig. 9, extending only to the transverse groove 102 at the tip line.

In applying direct sole-leveling pressure to the bottom of the shoe A the pad 84 operates in much the same manner as the pads described above. When pressure is applied to the shoe bottom the relatively hard non-compressible layer 88 will bend or flex sufficiently to conform itself substantially to the curvature of the shoe bottom

without filling in any depressions or hollows that may exist in the outsole 56. As the pressure increases the layer of soft rubber 90 will permit a limited amount of compression to take place over the entire shoe bottom thereby facilitating the conformation of the hard layer 88 to the shape of the outsole. The thick rubber material 92 supporting the central portion of the shoe-engaging wall rearwardly of its tip line permits the heel, shank and part of the toe portion of the shoe to sink a substantial distance into the pad without compressing the wall 86. Forwardly of the tip line the shoe cannot sink so far into the pad owing to the hard layer 96 which cannot be compressed as much as the soft material 92. The transverse slot 102 at the tip line permits the pad to bend upwardly under pressure to insure that the wall 86 will engage and press against the shoe bottom forwardly of said tip line. This construction permits sole-leveling pressure to be applied to the toe end of the shoe bottom without exerting sufficient pressure to force the shoe against the shoe-engaging wall a distance great enough to cause the outer layer of the shoe-engaging wall to crack. It has been found in operation that the pad 84 is very successful in leveling shoe bottoms the angles or toe springs of the foreparts of which are relatively great. The transverse groove 104 at the ball line permits the forepart of the pad to be adjusted angularly with respect to its rear portion as explained above.

Having described my invention, what I claim as new and desire to secure by Letters Patent of the United States is:

1. A pad for use in applying pressure to shoe bottoms having a hard but relatively flexible shoe-engaging surface supported at different portions by resilient material integral with such portions, the yielding capacity of the material supporting each of said portions being different from that of the material supporting other portions.

2. A pad for use in applying pressure to shoe bottoms comprising a member having a hard but somewhat flexible shoe-engaging wall supported at its marginal portion by integral resilient material which is softer than said wall and supported inwardly of said marginal portion by still softer resilient material.

3. A pad for use in applying pressure to shoe bottoms having a relatively hard shoe-engaging surface capable of flexing somewhat under pressure supported by resilient material integral with said surface and capable of yielding considerably under pressure, and a groove in said resilient material approximating in outline the periphery of the largest shoe which is to be operated upon.

4. A pad for use in applying pressure to shoe bottoms having a hard, relatively non-compressible shoe-engaging wall capable of bending without cracking under pressure, a thick layer of relatively compressible material integral with and supporting said wall, and a groove in said compressible material extending transversely of the shoe-engaging wall, said groove being located substantially opposite the ball line of a shoe operatively positioned on the pad.

5. A pad for use in applying pressure to shoe bottoms comprising a resilient member having a hard but somewhat flexible shoe-engaging wall overlying relatively yieldable resilient material integral with said wall, said yieldable material having formed therein a peripheral groove approximating in outline the shape of the bottom

of the largest shoe which can be operated upon, said yieldable material also having a groove extending transversely of the shoe-engaging wall and arranged to underlie the ball line of a shoe 5 operatively positioned on the pad.

6. A pad for use in applying pressure to shoe bottoms comprising a resilient member having a substantially non-compressible shoe-engaging surface capable of some flexion under pressure,

10 relatively soft resilient material approximating in outline the periphery of a large shoe supporting the central portion of said surface, resilient material harder than said soft resilient material but softer than said shoe-engaging surface sup-

15 porting the marginal portion of said surface, a groove separating the soft resilient material from the harder resilient material, and a readily removable layer of flexible material attached to said soft resilient material.

20 7. A pad for use in applying pressure to shoe bottoms comprising a resilient member having a relatively non-compressible but somewhat flexible shoe-engaging wall composed of a plurality of alternate layers of hard rubber and fabric

25 material, relatively soft rubber integral with and underlying the central portion of said wall, said soft rubber approximating in outline the periphery of the largest shoe to be operated on, harder rubber reinforced with fabric material integral

30 with and supporting the marginal portion of said wall, a relatively deep groove between the soft rubber and the harder rubber, and a groove ex-

35 tends transversely of the pad at approximately the ball line of a shoe operatively positioned thereon.

8. A pad for use in applying pressure to shoe bottoms comprising a resilient member provided with a relatively hard shoe-receiving surface capable of bending somewhat under pressure,

40 materials of different resiliency supporting different portions of said surface and each mate-

rial being capable of yielding under pressure an amount different from the yielding capacities of the materials supporting the other portions, and

45 a cover for said surface comprising a thin lay-

er of flexible material.

9. A pad for use in applying pressure to shoe bottoms comprising a resilient member having a shoe-engaging wall composed of an outer layer

50 of hard material capable of flexing somewhat under pressure and an inner layer of softer material capable of yielding under pressure, said wall being supported inwardly of its margin by resilient material more yieldable than said inner lay-

55 er, and being supported at said margin by rela-

tively hard resilient material.

10. A pad for use in applying pressure to shoe bottoms comprising a resilient member having a shoe-engaging wall composed of an outer layer

60 of hard material capable of flexing somewhat under pressure and an inner layer of relatively soft resilient material capable of yielding under pressure, said wall being supported inwardly of its margin by resilient material more yieldable than

65 said inner layer, and being supported at said margin by relatively hard resilient material, said supporting materials being separated from each other by a groove.

11. A pad for use in applying pressure to shoe

70 bottoms comprising a resilient member having a shoe-engaging wall composed of a thin outer layer of relatively hard material capable of flexing under pressure and a relatively thick inner layer of resilient material softer than said outer

75 layer and capable of yielding somewhat under

pressure, said wall being supported inwardly of its marginal portion by integral resilient material softer than said inner layer and capable of yielding substantially under pressure, and being supported at said marginal portion by resilient 5 material integral with said portion and softer than said outer layer but harder than said inner layer and the resilient material inwardly of said marginal portion.

12. A pad for use in applying pressure to shoe 10 bottoms comprising a resilient member having a shoe-engaging wall composed of a hard outer layer capable of flexing somewhat without compressing under pressure and an integral resilient inner layer capable of yielding under pressure, said 15 wall being supported inwardly of its marginal portion by soft resilient material integral there- with and more yieldable than said inner layer, and being supported at said marginal portion by

20 relatively hard resilient material integral there- with and yieldable only under substantial pres- 25 sure, said pad having a groove extending between said soft resilient material and said hard mate- rial and having another groove extending through

30 said materials transversely of the pad and ar- ranged to underlie the ball line of a shoe opera- 35 tively positioned thereon.

13. A pad for use in applying pressure to shoe 30 bottoms comprising a resilient member having a shoe-engaging wall composed of an outer layer 35 of relatively hard material capable of flexing somewhat under pressure and a relatively thick inner layer of resilient material softer than said outer layer, said wall being supported at the forward portion of the pad by a relatively soft 40

35 layer of resilient material overlying a relatively hard layer of resilient material, and being sup- 45 ported at the rear portion of the pad by rela- tively soft resilient material extending only to the margin of said portion and by relatively hard 50 resilient material at said margin.

14. A pad for use in applying pressure to shoe 45 bottoms comprising a resilient member having a shoe-engaging wall composed of an outer layer of relatively hard material capable of flexing 50 somewhat under pressure and an inner layer of

55 relatively thick resilient material softer than said outer layer and capable of yielding somewhat un- 60 der pressure, said wall being supported inward- 65 ly of the margins of its intermediate and rear portions by resilient material softer than said inner layer and being supported at said margins by

70 resilient material harder than said inner layer but softer than said outer layer, the forward por- 75 tion of said wall being supported by a continuous layer of resilient material softer than said inner layer overlying another continuous layer of resili- 80 ent material which is substantially as hard as the material supporting the margins of the interme- diate and rear portions of the shoe-engaging wall. 85

15. A pad for use in applying pressure to shoe 80 bottoms comprising a resilient member having a shoe-engaging wall composed of an outer layer of relatively hard material capable of flexing some- 85 what under pressure and a relatively thick inner

90 layer of material yieldable under pressure, the forward portion of said wall rearwardly to about the tip line of a shoe operatively positioned there- 95 on being supported by a relatively thick layer of soft resilient material more yieldable than said inner layer overlying a similar layer of resilient material considerably harder than said inner layer, the marginal portion of said wall rear- 100 wardly of said tip line being supported by rela- tively hard resilient material and said wall being 105

supported inwardly of said marginal portion by relatively soft resilient material, the two last-named supporting materials being separated by grooves extending lengthwise of the pad and terminating at the tip line.

16. A pad for use in applying pressure to shoe bottoms comprising a resilient member having a shoe-engaging wall composed of an outer layer of hard material capable of flexing somewhat under pressure and a relatively thick inner layer of material yieldable under pressure, the forward portion of said wall rearwardly to about the tip line of a shoe operatively positioned thereon being supported by a relatively thick layer of soft resilient material more yieldable than said inner layer overlying a similar layer of resilient material considerably harder than said inner layer, the marginal portion of said wall rearwardly of said tip line being supported by relatively hard resilient material and said wall being supported inwardly of said marginal portion by relatively soft resilient material, said last-named materials being separated by longitudinal grooves separated by a distance approximately equal to the width of the largest shoe to be operated on and terminating approximately at said tip line.

17. A pad for use in applying pressure to shoe bottoms comprising a resilient member having a shoe-engaging wall composed of a hard outer layer of relatively non-compressible material capable of bending somewhat under pressure and a relatively thick inner layer of soft resilient material, said wall being supported for substantially the full width of its forward portion rearwardly to about the tip line of a shoe operatively positioned thereon by a thick continuous layer of resilient material softer than said inner layer and overlying a relatively hard continuous layer of resilient material of substantially the same thickness, said wall being supported rearwardly of said tip line by hard resilient material at its margins and by soft resilient material inwardly of its margins, the two last-named materials being separated by grooves extending lengthwise of the pad and terminating at the tip line, said materials being also provided with grooves extending transversely of the pad substantially at the tip line and the ball line of a shoe operatively positioned thereon.

FRANK R. MERRITT. 25
